Duell, Washburn & Dwell
ATTORNEY

UNITED STATES PATENT OFFICE.

GEORGE GOULD GOING, OF MIDDLETON, CONNECTICUT, ASSIGNOR, BY MESNE ASSIGNMENTS, TO REMINGTON-NOISELESS TYPEWRITER CORPORATION, A CORPORATION OF NEW YORK.

TYPEWRITING MACHINE.

Application filed January 10, 1924. Serial No. 685,348.

To all whom it may concern:

Be it known that I, GEORGE GOULD GOING, a citizen of the United States, residing at Middletown, in the county of Middlesex and State of Connecticut, have invented certain new and useful Improvements in Typewriting Machines, of which the following is a full, clear, and exact description, such as will enable others skilled in the art to which it appertains to make and use the same.

This invention relates to typewriting machines and with regard to certain more specific features thereof, to mechanisms associated with the key levers for operating the type bars.

The object of the invention generally stated is to provide mechanism, which is efficient, economical and readily manufactured, adapted for associating with typewriter key levers to give the type bars a rectilinear motion upon the operation of the key levers.

Another object of the invention is to provide type bar actuating mechanisms capable of directly engaging with the type bars and functionally adapted to carry out the printing substantially without noise.

Other objects of the invention will be in part obvious and will in part appear hereinafter.

The invention accordingly comprises the features of construction, combinations of elements, and arrangement of parts, which will be exemplified in the construction herein-after set forth and the scope of the application of which will be indicated in the claims.

For a fuller understanding of the nature and objects of the invention reference should be had to the following detailed description taken in connection with the accompanying drawing, in which:

Figure 1 is a side elevation showing, in normal position, such parts of the mechanism as are necessary to understand one embodiment or application of the present invention; and

Fig. 2 is a side elevation of the mechanism showing the position of the members after operation.

Referring to the drawing, 10 indicates a frame, carrying a base plate 11, a top plate 12, and a bracket 13. The type bar 14 carrying type characters 33 is horizontally disposed on the members 11, 12, and 13 so that

it is capable of executing rectilinear motion. The movement of the type bar in a forward or printing direction is limited by the platen roller 15 disposed on the frame 10. Movably mounted on the frame, and limited in movement by the resilient stops 17 and 18, is a key lever 16 for operating the type bar 14, and the actuating mechanism therefor, to be described hereinafter, which is adapted for transmitting the motion to the type bar with a negative acceleration.

Fixed to the type bar 14 by suitable means, such as pins 21, is a rack 19. This rack is adapted to receive the motion which actuates the type bar. The motion is communicated from the actuating mechanism which preferably is in substantially rolling contact therewith.

The actuating mechanism, as illustrated, includes the toothed member or sector 24, pivotally and eccentrically mounted on shaft or pivot 23, which is carried by bracket 13. The sector 24 is shaped to have a gradually decreasing radius from the front portion 25 to the rear portion 26. The front portion 25 is adapted to mesh with the curved portion 20 of the rack 19 while the rear portion 26 is made straight and extends at substantially right angles to the shortest radius of the sector adapting it for meshing with the straight portion 22 of the rack. In constructing the sector the portion 26 is so disposed that it meshes with the straight portion of the rack when the latter reaches its forward position.

Formed integral with the sector is a momentum accumulator or inertia device 27 having a radius approximately equal to the radius of the forward portion 25 of the pinion sector. It is not necessary to construct the momentum accumulator 27 with such a radius but such a construction suits the typewriter assemblage.

The link 28 connects the key lever 16 to the pinion sector 24 engaging the sector at a point 29. The point 29 lies forward of a vertical line through the axis of the shaft 23 when the parts of the mechanism are in their normal positions as shown in Fig. 1. By locating the point of engagement of the link 28 and sector 24 as near as permissible in view of other constructional features, to a horizontal line through the axis of the shaft

23 and at right angles to the initial line of action of the link 28 the initial movement of the sector is facilitated.

In order to provide for the return of the sector 24, and consequently the other parts of the mechanism to their normal positions after operation, a spring 30 is connected between a post 31, carried by the member 13, and the sector 24. As shown in Fig. 1 the point 32 at which the spring 30 is connected to the sector 24 lies near the line extending between post 31 and the axis of the shaft 23. The spring 30 is aided in the return of the parts to their normal positions by a spring 34 mounted on the frame 10 so that it contacts with the key lever 16 and is energized by the downward movement of the latter.

The operation of the mechanism is as follows:

20 The parts of the mechanism are retained in their normal positions shown in Fig. 1 by the action of the spring 30. The type bar actuating mechanism including the sector 24 and the rack 19 is set in operation 25 by means of the key lever 16. Upon the pressing downward of the key lever 16, motion is imparted through the link 28 to the sector 24 rotating the latter forward about the shaft 23. Since the sector 24 meshes 30 with the rack 19, the type bar 14 is set in motion. As above set forth, and as shown in the drawings, the sector 24 is of gradually decreasing radius from the front portion 25 to the rear portion 26. Consequently as the pinion sector rotates, its point of contact with the rack 19 gradually approaches the axis of the shaft 23 thus giving the type bar a printing movement having a negative acceleration. The sector 24 35 and the rack 19 are also adapted for giving the type bar a rectilinear motion.

After the sector 24 has been given a small angular movement by the operation of the key lever 16, the momentum accumulator or 45 inertia device 27 which has stored up a certain amount of energy is carried to a position where a line through the axis of the shaft 23 and the center of gravity of the device 27 lies near the horizontal. In this position 50 the moment of the accumulator due to the influence of gravity, reaches its maximum. The accumulator or inertia device will, therefore, first aid in the completion of the printing movement of the type bar and then impart through the sector and rack, a printing impulse. As the type bar moves forward its speed gradually decreases until it reaches its printing position. Consequently the type bar is not projected against the platen at a 55 high rate of speed but moves slowly and noiselessly into its printing position which it reaches when the straight portions of the rack 19 and sector 24 mesh. The printing impulse or pressure is then applied along the 60 line of movement of the type bar. After 65

the printing stroke has been completed the spring 30, tensioned by the operation of the moving parts, acts along a line nearly at right angles to a line extending through the axis of the shaft 23 and the point 32 at which the spring is connected to the sector 24. This action of the spring 30 aided by the action of spring 34 returns the members of the mechanism to their normal positions, shown in Fig. 1.

75 From the above description, it will be seen that the present invention embodies a simple and practical operating mechanism, permitting rapid and efficient operation of the machine, and is fully designed to accomplish 80 among others, all of the objects and advantages set forth above.

85 Since certain changes may be made in the above construction and different embodiments of the invention could be made without departing from the scope thereof, it is intended that all matter contained in the above description or shown in the accompanying drawing shall be interpreted as illustrative and not in a limiting sense.

90 Having described my invention what I claim as new and desire to secure by Letters Patent is:

1. In a typewriting machine, in combination, a platen, a type bar adapted to approach the platen rectilinearly, actuating means therefor, including a key lever and a pivoted member arranged to make substantially rolling contact with said type bar and impart motion thereto which has a negative acceleration during the final stage, and an inertia device for imparting a pressure printing impulse to said type bar at the end of said final stage.

105 2. In a typewriting machine, in combination, a platen, a type bar adapted to approach the platen rectilinearly, and actuating means therefor, including a key lever and a pivoted member arranged to make substantially rolling contact with said type bar, and impart motion thereto which has a negative acceleration during the final stage, said pivoted member having a portion adapted by its 110 inertia to impart a pressure printing impulse to said type bar at the end of said final stage.

115 3. In a typewriting machine, in combination, a platen, a type bar having a rack and adapted to approach the platen rectilinearly, and actuating means therefor, including a key lever and a toothed member arranged to mesh said rack and impart motion to the type bar which has a negative acceleration during the final stage.

120 4. In a typewriting machine, in combination, a platen, a type bar having a rack adapted to approach the platen rectilinearly and actuating means therefor, including a key lever and a toothed member adapted to mesh said rack, the locus of contact between 125

said rack and toothed member being one having a negative characteristic for the acceleration imparted.

5. In a typewriting machine, in combination, a platen, a type bar having a rack and adapted to approach the platen rectilinearly and actuating means therefor, including a key lever and a toothed member adapted to mesh said rack, the locus of contact between said rack and toothed member being one having a negative characteristic for the acceleration imparted, and an inertia element arranged to impart a pressure printing impulse to the type bar at the end of its approach to the platen.

10 6. In a typewriting machine, in combination, a platen, a type bar having a rack and adapted to approach the platen rectilinearly, and actuating means therefor, including a key lever and a toothed member arranged to mesh said rack and impart motion to the type bar which has a negative acceleration during the final stage, said toothed member having a weighted portion adapted to impart a pressure printing impulse to the type bar at the end of said final stage.

15 7. In a typewriting machine, in combination, a platen, a type bar having a rack and adapted to approach the platen rectilinearly and actuating means therefor, including a key lever and a toothed member adapted to mesh said rack, the locus of contact between said rack and said toothed member being substantially a spiral having a decreasing radius as the type bar approaches the platen.

20 8. In a typewriting machine, in combination, a platen, a type bar having a rack and adapted to approach the platen rectilinearly and actuating means therefor, including a key lever and a toothed member adapted to mesh said rack, the locus of contact between said type bar and said toothed member being substantially a spiral having a decreasing radius as the type bar approaches said platen, and also a final straight portion.

25 9. In a typewriting machine, in combination, a platen, a type bar having a rack and adapted to approach the platen rectilinearly and actuating means therefor, including a key lever and a toothed member adapted to mesh said rack, the locus of contact between said type bar and said toothed member being substantially a spiral having a decreasing radius as the type bar approaches said platen, and also a final straight portion, and an inertia device for imparting a pressure printing impulse to said type bar when the flat portion of said type bar and toothed member engage.

30 10. In a typewriting machine, in combination, a platen, a type bar having a rack and adapted to approach the platen rectilinearly, and actuating means therefor, including a key lever and a toothed member adapted to mesh said rack, the locus of contact between

said type bar and said toothed member being substantially a spiral having a decreasing radius as the type bar approaches said platen, and also a final straight portion, said toothed member having a weighted portion adapted to impart a pressure printing impulse to said type bar when the flat portions of said type bar and toothed member are in engagement.

35 11. In a typewriting machine, in combination, a platen, a type bar adapted to approach the platen rectilinearly and provided with a curved toothed rack, a pivoted toothed member adapted to engage with said rack having a spiral locus of contact of decreasing radius as the platen is approached, a key lever, and operating connections between said key lever and said toothed member.

40 12. In a typewriting machine, in combination, a platen, a type bar adapted to approach the platen rectilinearly and provided with a curved toothed rack, a pivoted toothed member adapted to engage with said rack having a spiral locus of contact of decreasing radius as the platen is approached, a key lever and operating connections between said key lever and said toothed member, said rack and toothed member being provided with a flat portion adapted to engage at the final stage of its approach to the platen.

45 13. In a typewriting machine, in combination, a platen, a type bar adapted to approach the platen rectilinearly and provided with a curved toothed rack, a pivoted toothed member adapted to engage with said rack having a spiral locus of contact of decreasing radius as the platen is approached, a key lever and operating connections between said key lever and said toothed member, said rack and toothed member being provided with a flat portion adapted to engage at the final stage of its approach to the platen, and an inertia device for imparting the pressure printing impulse to the type bar when said flat portions engage.

50 14. In a typewriting machine, in combination, a platen, a type bar adapted to approach the platen rectilinearly and provided with a curved toothed rack, a pivoted toothed member adapted to engage with said rack having a spiral locus of contact of decreasing radius as the platen is approached, a key lever and operating connections between said key lever and said toothed member, said rack and toothed member being provided with a flat portion adapted to engage at the final stage of its approach to the platen, said toothed member having a weighted portion adapted to impart a pressure printing impulse to said type bar when said flat portions engage.

55 15. In a typewriting machine, in combination, a frame, a type bar movably mount-

ed on the frame, a curved rack carried by the type bar, a key lever, a pinion sector of gradually decreasing radius connected to the key lever, said pinion sector being adapted 5 to engage positively the curved rack and to give the type bar a rectilinear motion upon the operation of the key lever, a momentum accumulator carried by the pinion sector for imparting a printing impulse to said type 10 bar, and a spring interposed between the frame and pinion sector for returning the parts to their normal positions.

16. In a typewriting machine, in combination, a key lever, a pinion sector of gradually decreasing radius connected to the key 15 lever, a type bar, means carried by the type bar adapted to cooperate with the pinion sector to give the type bar a rectilinear motion having a negative acceleration upon the 20 operation of the key lever, a momentum accumulator carried by the pinion sector for imparting a printing impulse to the type bar, and means provided in conjunction with the pinion sector for returning the parts to 25 their normal positions.

17. In a typewriting machine, in combination, a movable type bar, a rack carried by the type bar, a key lever, a pivotally mounted pinion sector connected to the key 30 lever and in mesh with the rack, a momentum accumulator carried by the pinion sector, said pinion sector and rack being adapted to impart to the type bar along its line 35 of motion a printing impulse received from the momentum accumulator.

18. In a typewriting machine, in combination, a movable type bar, a rack carried by the type bar, a key lever, a revolvably and eccentrically mounted toothed sector 40 connected to the key lever, said sector and rack being mounted, constructed and arranged so that the sector gains momentum under the action of gravity as it revolves in

the printing movement and co-acts with the rack to give the type bar a rectilinear move- 45 ment with a negative acceleration and to impart to the type bar along its line of movement the momentum of the sector, giving it a printing impulse.

19. In a typewriting machine, in combination, a type bar, a rack comprising a curved portion and a straight portion carried by the type bar, said rack being so disposed that the straight portion lies parallel to the line of movement of the type bar, 55 a pinion sector comprising a curved portion of gradually varying radius and a straight portion extending at right angles to a radius, the curved portion of said rack and pinion sector being adapted to co-act to give 60 the type bar a negatively accelerated printing motion and the straight portions to transmit to the type bar, along its line of movement, a printing impulse and a key lever for operating the pinion sector. 65

20. In a typewriting machine, in combination, a movable type bar, a rack comprising a curved portion and a straight portion carried by the type bar, said rack being so disposed that the straight portion lies parallel to the line of movement to the type bar, 70 a pinion sector comprising a curved portion of gradually varying radius and a straight portion extending at right angles to a radius, a momentum accumulator carried by the pinion sector, said curved portions of the rack and pinion sector being 75 adapted to co-act to give the type bar a printing movement with a negative acceleration and the straight portions to transmit to 80 the type bar a printing impulse received from the momentum accumulator, and a key lever for operating the pinion sector.

In testimony whereof I affix my signature.

GEORGE GOULD GOING.
